UNITED STATES PATENT OFFICE.

JOHN C. BROOKS, OF PATERSON, NEW JERSEY, ASSIGNOR TO OSSIAN T. WAITE, OF OSHKOSH, WISCONSIN.

LOOM.

1,269,375.

Specification of Letters Patent. Patented June 11, 1918.

Application filed May 5, 1917. Serial No. 166,601.

To all whom it may concern:

Be it known that I, JOHN C. BROOKS, a citizen of the United States, residing at Paterson, in the county of Passaic and State 5 of New Jersey, have invented certain new and useful Improvements in Looms, of which the following is a specification.

The present invention has to do with certain improvements in the construction of 10 looms for weaving fabric, and the features of invention herein disclosed are very well adapted for use in connection with looms for weaving fabrics such as grass rugs and the like, which are woven from grass twine 15 and other comparatively large and heavy or coarse material.

In the usual type of loom the warp threads feed continuously through the machine, being fed from large spools or bundles. 20 These spools or bundles may be made as large as desired so as to accommodate as much warp material as may be necessary for the complete weaving operation. However, the weft thread or twine has been carried in 25 a shuttle or the like, and consequently the amount of such material which could be carried in a continuous piece has been limited by the size and capacity of the shuttle.

Where the material is large and bulky, as 30 is the case with grass twine and the like, only a comparatively small length of the material can be put into a shuttle of reasonable size, so that the amount of fabric which can be continuously woven without 35 having to replace or replenish the shuttle is comparatively limited. This means not only that it is necessary to frequently replace or replenish the shuttle, but also means that the weft thread or twine will be broken up 40 into comparatively short lengths. Consequently, the fabric itself will be discontinuous as regards the weft thread and will, therefore, not have the strength and wearing qualities which it would have if said thread 45 or yarn were continuous.

One of the objects of the present invention is to provide a loom of such construction and arrangement that the weft threads may be fed back and forth through the ma- 50 chine by a carrier or traveler which takes said thread from a large continuous mass

or body located at a fixed point outside of or away from the traveler itself. By this means or arrangement the amount of weft twine which can be used as a continuous 55 unbroken piece will not in any sense be limited by capacity of the moving or traveling part, but will be limited only by the size of the ball or mass of twine which may be conveniently mounted at a stationary point 60 adjacent to the loom itself.

In order to secure a fabric of special design or weave, it may be desirable to use two or more weft threads or twines simultaneously. In some cases, for example, it may be 65 desired to use a weft composed of heavy yarns or twine such as grass twine, and also another weft of linen or cotton thread and of comparatively small size.

Another feature of my invention has to 70 do with the provision of a construction such that two or more wefts may be simultaneously woven into the fabric for the purposes above mentioned. In this connection, another object is to so construct and ar- 75 range the machine that one of said wefts may be fed in continuously by a traveler, such as has been previously mentioned, the other weft being fed in from a shuttle of ordinary construction. 80

Other objects and uses of the invention will appear from a detailed description of the same, which consists in the features of construction and combinations of parts hereinafter described and claimed. 85

Referring to the several drawings:

Figure 1 shows a plan view of the assembled machine, the traveler being at the extreme right-hand limit of its movement;

Fig. 2 shows a front elevation of the ma- 90 chine, being an elevation of the machine looking in the same direction in which Fig. 1 is observed;

Fig. 3 shows a section taken on the line 3—3 of Fig. 1, looking in the direction 95 of the arrows. It may also be considered a section taken on the line 3—3 of Fig. 4, looking in the direction of the arrows;

Fig. 4 shows a longitudinal section taken on the line 4—4 of Fig. 2, looking in the di- 100 rection of the arrows. This figure may also be considered as being taken on the

line 4—4 of Fig. 1, looking in the direction of the arrows;

Fig. 5 shows a detailed view of one of the cams and immediately associated parts which operate the opening and closing of the reeds;

Fig. 6 shows a detailed view of the cam and immediately associated parts which control the warp yarn take-up bar;

Fig. 7 shows a detailed view of the cam and immediately associated parts which control the engaging and disengaging of the traveler with its operating shaft;

Fig. 8 shows a detailed view of the cam and immediately associated parts which control the crossing and uncrossing of the blades for the warp threads or twine;

Fig. 9 shows a detailed view of the cam and immediately associated parts which control the back and forth movements of the sword arms;

Fig. 10 shows a fragmentary side elevation of the traveler and the pivoted extension thereof;

Fig. 11 shows a fragmentary plan view corresponding to Fig. 10, a portion of the traveler being cut away on a horizontal section to reveal the construction of the tripping pin, and the operative position of the tripping pin being shown by means of dotted lines;

Figs. 12 and 12^a show plan and elevational views of the main operative parts in what I shall designate the initial position of a cycle of movements;

Figs. 13 and 13^a show similar views of the said parts at the next major movement in the cycle of operations;

Figs. 14 and 14^a show similar views of similar parts at the next major movement in the cycle of operations;

Figs. 15 and 15^a show similar parts at the next major movement in the cycle of operations; and in like manner

Figs. 16, 16^a, 17 and 17^a, 18 and 18^a and 19 and 19^a show similar views of similar parts in four consecutive major movements in the cycle of operations, which will restore the parts to a position wherein the next major movement will bring them back to the condition shown in Figs. 12 and 12^a.

Referring now to the several figures, I will describe the particular embodiment of the features of my invention illustrated therein. In the said embodiment I have shown a rod or shaft 20 on which the various warp threads or yarns 21 are carried. These threads or yarns pass over a whip roll 22 and through the upper and lower guides 23 and 24, respectively. One set of warps passes over the guide 23 and the other set passes under the guide 24. Corresponding to the guide 23 and the warps passing over the same, are the upper blades 25, and the lower blades 26 which correspond to the up-

per and lower warps which pass over and under the guides 23 and 24.

The blades 25 are mounted on a rock shaft 27 and the blades 26 are mounted on a rock shaft 28. The rock shaft 27 carries a segmental gear 29. A segmental rack 30, meshing with the gear 29, is pivoted to a stationary part at the point 31, and a crank arm 32 is connected to the segmental gear 30. The crank arm 32 connects to the rock shaft 28 through the medium of the crank arms 33 and 34 and the connecting link 35. By reason of this construction the rocking of the crank 32 will cause the rock shafts 27 and 28 to rock in opposite directions, so as to cause the sets of blades 25 and 26 to rock simultaneously in opposite directions.

In their outer ends the blades 25 and 26 are provided with suitable openings for the accommodation of the warps, so that said warps will be deflected up and down by the reciprocation of the blades. Suitable tensioning mechanism may be provided for withdrawing the completed fabric 36. I do not show such mechanism, simply for the reason that it may be of any one or a number of familiar forms.

In the lower portion of the machine there are pivoted the sword arms 37 and 38. These are pivoted one at each side of the machine, and are connected by the top cross-piece 39. The upper reed bars 40 depend from the cross-piece 39. Between the sword arms there is slidably mounted another cross-piece 41, which is carried on the upper ends of the rods 42 and 43. Said rods can be operated within the guides or bearings 44 and 45 carried by the sword arms 37 and 38, respectively. The cross bar 41 carries the lower reed bars 46, which correspond to the upper reed bars 40, so that upon raising the bar 41 the lower reed bars 46 will be brought into engagement with the respective reed bars 40. The reed bars are so spaced as to accommodate the various warp threads or yarns between them during the operations of packing up the fabric.

The sword arms 37 and 38 may also be provided with a cross rod or bar 47 having openings for the accommodation of the lower reed bars 46. This cross bar 47 may be provided in its upper face with slots corresponding to the spaces or intervals between the lower reed bars 46, said slots being for the accommodation of the warp threads or yarns when the blades are at their extreme positions of movement. In those cases where a shuttle is to be used in combination with the traveler, said shuttle may be shot back and forth over the bar 47 as a track-way. In such cases also any suitable form of shuttle-throwing arms 48 and 49 may be adopted, and in view of the fact that such constructions are well known in the art, I will not describe the same in detail. For 130

purposes of convenience I have indicated a simple form of shuttle by the numeral 50.

Referring to the several figures, there will be found a cross shaft 51, located in front of the position occupied by the rock shafts 27 and 28. Said cross shaft 51 is provided with the double threads 52 and 53 which lie in opposite directions. Consequently, a traveler mounted on the shaft will be thrown in the one direction or the other, depending upon which of the threads 52 or 53 is engaged, and the shaft 51 may nevertheless be rotated continuously in the same direction.

Slightly behind the shaft 51 is a cross rod 54. A traveler 55 is slidably mounted on the shaft 51 and on the cross rod 54, and said traveler is retained against movement out of a given plane by reason of its simultaneous engagement with the shaft 51 and the rod 54. That is to say, the traveler is thus caused to reciprocate back and forth in a fixed plane of movement. In the front portion of the traveler there is slidably mounted a pin 56, and a spring 57 tends at all times to draw said pin into engagement with one of the threads of the shaft 51. A lever 58 is pivoted to the traveler at the point 59, the upper end of said lever being connected to the pin 56, and its lower end being provided with a contacting head 60. The shaft 51 turns over in the direction of the arrows shown in Figs. 1 and 4.

The slot 53 extends over and terminates in a circular slot 61 at the left hand side of the machine, the slot 52 not being carried into the slot 61 but terminating at the face thereof. In like manner the slot 52 runs clear over to the right-hand end of the shaft 51 and terminates in a circular slot, the slot 53 not being extended into said circular slot, but terminating at the face thereof.

It, therefore, follows that if the traveler be standing at the right-hand side of the machine, namely, the position shown in Figs. 1, 2 and 4, and the pin 56 be then allowed to drop into the circular slot at the right-hand end of the shaft 51, the slot 52 will take hold of the inner end of the pin 56 and cause the traveler to be thrown or moved to the left-hand side of the machine.

If the pin 56 be withdrawn against the force of the spring 57 as soon as the traveler has reached the extreme left-hand limit of movement, then the traveler will stand at said left-hand limit of movement until the pin 56 may again be allowed to drop into the circular slot 61, whereupon it will be engaged by the slot 53 and caused to advance back to the right-hand side of the machine. It is thus possible to move the traveler back and forth alternately, simply by controlling the movements of the pin 56 at the proper time under the influence of the spring 57.

For the purpose of controlling the movements of the pin 56 I have provided the bell

cranks 62 and 63 at the right and left-hand sides of the machine, respectively. These bell cranks have at their upper ends the cam surfaces 64 and 65, respectively, which cam surfaces are so placed and formed that the following actions are secured: Assuming the bell crank 62 to stand with its upper end tilted rearward,—that is, toward the shaft 51—when the traveler approaches the extreme right-hand limit of movement, the contacting surface 60 will ride up onto the surface 64, thus rocking the lever 58 and withdrawing the pin 56 against the force of the spring 57. If the bell crank 62 be then rocked in the opposite direction,—that is, away from the shaft 51—the pin 56 will be allowed to move into engagement with the thread 52 under the influence of the spring 57.

Assuming the bell crank 63 to be standing with its cam surface 65 in the rearward position,—that is, moved toward the shaft 51—as the traveler approaches the extreme left-hand limit of movement, the contacting head 60 will ride up on to the cam surface 65, thus withdrawing the pin 56 against the force of the spring 57 and disengaging the traveler for the time being from the influence of the slots of the shaft 51.

In the front portion of the traveler there is provided a perforation or opening for the accommodation of the weft thread or yarn 66, which yarn may be taken from a spool or bundle conveniently mounted at any suitable point adjacent to the machine. The forward portion of the traveler carries an extension 67 pivoted to the forward end of the traveler at the point 68. Said extension may be swung or raised upwardly on the pivot 68, but cannot fall below a limit of movement substantially as shown in Fig. 4.

The extension 67 is provided with a perforation entering its right-hand side and leaving at its rear end, and the yarn 66, aligned along the right side of the face of the traveler, may be fed through said perforation and delivered from the rear end of the traveler in the manner best shown in Figs. 1 and 4. Manifestly, when the extension 67 lies in direct alignment with the main portion of the traveler, a minimum length of yarn will be necessary to reach from the source of supply to the completed fabric, whereas by tilting or raising the extension 67 upward on the pivot 68 an additional amount or slack portion of yarn will be necessary, and consequently this additional portion will be withdrawn from the source of supply by bending or tilting the extension on the pivot 68.

The whip roll or rod 22 is conveniently mounted on a pair of arms 69 and 70 which extends upward from a rock shaft 71. In Fig. 4 the rock shaft and the arms 69 and 70

with the whip roll 22 are shown tilted into the extreme forward position,—that is, away from the shaft 51. They may be rocked or tilted so as to carry the bar 22 toward the shaft 51 when desired.

I will now describe briefly the cycle of movements of the various parts, and will then explain more in detail the particular mechanism which I have illustrated for securing the proper relationship in said movements. In describing these movements I will have reference particularly to Figs. 12 to 19^a inclusive, which show the main operative parts in their various consecutive positions. The position shown in Figs. 12 and 12^a may be termed the "initial position." In it the traveler stands at the left-hand side of the machine, the blades 25 and 26 are spread open, the reeds are separated, the sword arms stand in their rearward position, and the shuttle stands at the left-hand side of the machine.

The first movement consists in carrying the traveler to the right-hand side of the machine, the blades standing in the open position illustrated in Fig. 12^a. This cross-wise movement of the traveler will lay in a length of weft thread or yarn, as shown in Fig. 13. The reed dents will then be closed, as shown in Fig. 13^a. On each of the sword arms 37 and 38 there is a cam block 72 of the general form shown in Fig. 4. The upper face of each of these cam blocks is adapted to lift the extension 67 when the reed dents are brought together, said lifting operations being as shown in Fig. 13^a. Consequently, the act of closing together the reed dents will raise the extension 67 so as to withdraw the excess portion of weft yarn or twine.

The next operation in the cycle will consist in swinging the sword arms forward so as to pack up the length of weft thus placed. The sword arms will be immediately restored to their forward position.

The next operation will consist in reversing the blades 25 and 26 so as to reverse the positions of the warp twines. This condition is shown in Figs. 14 and 14^a. In those cases where a shuttle of ordinary form is to be used in conjunction with the traveler, said shuttle serving to carry an ordinary thread or yarn back and forth, the shuttle will next be shot from left to right so as to bring the parts into the position shown in Figs. 15 and 15^a. Thereafter, the sword arms with the reed dents closed, will be thrown forward and then back, so as to pack the length of twine thus laid.

Inasmuch as the blades 25 and 26 are crossed at the completion of the movement shown in Figs. 15 and 15^a, it will be necessary to uncross said blades before the traveler can be sent back to the left-hand side of the machine. Consequently, the next move-

ment will be to uncross the blades and also to open the reed dents, both of which conditions are depicted in Figs. 16 and 16^a.

The next movement, therefore, after that shown in Figs. 16 and 16^a will be to throw the traveler back to the left-hand side of the machine into the position shown in Fig. 17. This will lay the weft yarn or twine into position, so that upon the next forward movement of the sword arms, this lay will be packed into position. As soon as the traveler has reached the extreme left-hand limit of its movement, the reed dents will be brought together, thus raising the pivoted extension 67 of the traveler, and thus withdrawing an excess portion of twine or yarn. Thereupon the sword arms will be advanced and immediately retracted, so as to pack the yarn thus laid into position.

The next movement will be to reverse the blades 25 and 26, as shown by Fig. 18^a. Thereupon the shuttle may be shot back to the left-hand side of the machine into the position shown in Fig. 19, after which the sword arms will be thrown forward and back for the purpose of packing the weft thread thus laid into position.

It will be observed that in those positions shown in Figs. 13^a, 14^a, and 15^a, and in Figs. 17^a, 18^a, and 19^a, the reed dents are retained in closed position, so that the extension 67 is retained in raised position by means of the cam block 72 immediately beneath. This simultaneously raises the weft yarn or twine coming from the traveler, so that the same will be out of the way, and so as to provide sufficient clearance for the shuttle.

Having thus described the various movements to be performed by the different parts, I will now explain the particular construction of mechanism illustrated for performing these movements. These various movements are conveniently effected by the use of cams mounted on the shaft 73, which shaft performs one complete revolution for a complete cycle of movements of the main operative parts. A lever 74, pivoted at the point 75, carries a roller 76 adapted to be engaged by a cam 77 on the shaft 73. Said cam has two diametrically opposed dwells 78 and 79 of small radius, and two diametrically opposed dwells 80 and 81 of large radius. These dwells are not necessarily absolutely concentric with the shaft for the reason to be presently explained.

The lower end of the lever 74 is pinned to a link 82, the forward end of which link is pinned to a crank 83 mounted on a shaft 84, which shaft is journaled in the lower portions of the sword arms. The rods 42 and 43 for the lower set of movable reed dents 46 are provided with sleeves 85 and 86. Cranks 87 and 88 are mounted on the shaft 84, said cranks being connected to the sleeves 85 and 86 by means of the links 89 and 90.

A spring 91 tends to restore the shaft 84 to such a position as will lower the reed dents 46. Manifestly, with the arrangement thus described, the reed dents will be closed during the travel of the roller 76 on both of the dwells 80 and 81, whereas said reed dents will be opened during the travel of said roller on each of the dwells 78 and 79.

Mounted on the shaft 73 is another cam 92, which likewise has the diametrically opposed dwells 93 and 94 of small radius and the other diametrically opposed dwells 95 and 96 of large radius. A link 97 has its upper end connected to a crank 98 on the shaft 71 and its lower end carries a roller 99 engaging with said cam. The link 97 is also provided with a forked extension 100, which engages the shaft 73, so that the link 97 will at all times be properly centered on said shaft. Manifestly, with this arrangement, the slack whip roll 22 will stand in the forward position, while the roller 99 rides on either of the dwells 93 or 94, whereas said slack take-up device will stand in the rearward position, while said roller stands on either of the dwells 95 and 96.

Mounted on the shaft 73 adjacent to each side of the machine is a cam 101 having a long dwell of short radius 102 and a short dwell of longer radius 103. These cams 101 are for the bell cranks 62, which bell cranks carry the rollers 104 riding on their respective cams. With this arrangement it is manifest that as long as one of the rollers 104 rides on the dwell of short radius 102, the corresponding bell crank 62 will be tilted forward into position to disengage the pin 56 from the shaft 51, and to retain the pin in such disengagement. As soon, however, as the roller 104 rides up onto the dwell of longer radius, the corresponding bell crank 62 will be tilted backward and the pin 56 will thus be allowed to engage with the shaft 51.

Mounted on the shaft 73 is a face cam 105, consisting of a slot in the face of a plate. A lever arm 106 is pivoted to a stationary part at the point 107, the outer end of said lever arm being connected to the crank 32 by means of a link 108. The arm 106 has a roller 109 working in the cam slot. Said cam slot consists of a dwell 110 of short radius and a dwell 111 of longer radius. Manifestly, while the roller 109 travels in the dwell of short radius, the arm 106 will be lowered so as to open the blades into the position shown in Fig. 4, whereas when the roller 109 enters the dwell of longer radius, the arm 106 will be raised and the blades will be reversed. Mounted on the shaft 73 is another cam 112, consisting of a pair of enlargements 113 and 114, diametrically opposed to each other. A link 115 has its forward end connected to one of the sword arms by a pin 116, and its rear end is forked

at 117 to thereby engage the shaft 73 and sustain the rear end of the link. A roller 118, mounted on said link, engages the cam surfaces 113 and 114. A pair of springs 119 and 120 tend at all times to draw the sword arms rearwardly and thus retain the roller 118 against the cam 112.

In order to stop the machine in case of the breakage of the weft yarn or twine, I have illustrated a rod 121 journaled in the frame of the machine and carrying the upstanding crank arm 122. Within the traveler there is a horizontal slot 123, and a pin 124 is pivoted in said slot at the point 125. A spring 126 tends at all times to rock the pin 124 into the dotted line position shown in Fig. 11, but during the normal operation of the machine, as long as the weft twine or yarn lies in the normal position, the pin 124 will be retained in the full line position shown in Fig. 11. In case of breakage of this yarn or twine, however, said pin will be thrown into the dotted line position of Fig. 11, so that when the traveler reaches the extreme right-hand limit of movement, said pin will strike against the crank arm 122 and thus rock the rod 121 to thereby bring into movement such mechanisms as will bring the machine to rest.

While I have herein shown and described only a single embodiment of the features of my invention, still it will be understood that I do not limit myself to the said embodiment except as I may so limit myself in the claims.

I claim:

1. In a machine of the class described, the combination of a pair of sword arms, upper fixed reed dents connected to said arms, lower movable companion reed dents carried by the sword arms, upper and lower sets of vertically oscillatable warp guides, upper and lower sets of fixed warp guides, the upper warp guides oscillating in planes intermediate the planes of oscillation of the lower warp guides, a weft-feeding traveler, means for guiding the same in a horizontal direction of travel and between the upper and lower warp guides when said guides are respectively in their upper and lower positions, means for raising the lower movable reed dents into operative engagement with respect to the upper fixed reed dents, a shuttle guide on the sword arms, a shuttle traveling in said guide, means for throwing the sword arms forward and back for the purpose of packing a weft, means for oscillating the warp guides simultaneously in opposite directions to thereby cause the positions of said guides to cross each other, means for causing the traveler to advance alternately back and forth, and means for causing the shuttle to travel alternately back and forth along the shuttle guide.

2. In a machine of the class described, the

- combination of a pair of sword arms, upper fixed reed dents connected to said arms, lower movable companion reed dents carried by the sword arms, upper and lower sets of vertically oscillatable warp guides, upper and lower sets of fixed warp guides, a traveler, suitable guides for causing said traveler to travel in a horizontal direction intermediate the positions of the upper and lower sets of warp guides when said guides are respectively in their upper and lower positions, slack take-up means for the warps, a shuttle guide carried by the sword arms, a shuttle traveling in said guide, means for raising the lower movable reed dents into operative engagement with respect to the upper fixed reed dents, means for throwing the sword arms forward and back for the purpose of packing a weft, means for oscillating the upper and lower sets of warp guides simultaneously in opposite directions to thereby cause said warp guides to reverse their positions, means for causing the traveler to advance alternately back and forth when the warp guides stand in their normal positions, means for causing the shuttle to travel alternately back and forth along the shuttle guide when the sword arms stand in their normal positions, and means for operating the slack take-up mechanism.
3. In a machine of the class described, the combination of a pair of sword arms, upper and lower relatively movable companion sets of reed dents carried by the sword arms, upper and lower sets of vertically oscillatable warp guides, upper and lower sets of fixed warp guides, a traveler, suitable guides for causing said traveler to travel in a horizontal direction intermediate the positions of the upper and lower sets of warp guides when said guides are respectively in their upper and lower positions, slack take-up means for the warps, a shuttle guide carried by the sword arms, a shuttle traveling in said guide, means for moving the companion sets of reed dents into engagement with each other, means for throwing the sword arms forward and back for the purpose of packing a weft, means for oscillating the upper and lower sets of warp guides simultaneously in opposite directions to thereby cause said guides to reverse their positions, means for causing the traveler to advance alternately back and forth when the warp guides stand in their normal positions, means for causing the shuttle to travel alternately back and forth along the shuttle guide when the sword arms stand in their normal position, and means for operating the slack take-up mechanism.
4. In a machine of the class described, the combination of a pair of sword arms, upper and lower companion sets of relatively movable reed dents connected to said arms, upper and lower sets of vertically oscillatable

warp guides, upper and lower sets of fixed warp guides corresponding to the vertically movable warp guides, a traveler, means for guiding the same between said sets of warp guides when the movable warp guides are in their normal positions, a shuttle guide carried by the sword arms, a shuttle traveling in said guide, means for moving the companion sets of reed dents into relative engagement with each other, means for throwing the sword arms forward and back for the purpose of packing a weft, means for oscillating the upper and lower sets of movable warp guides to thereby cause said guides to reverse their positions, means for causing the traveler to advance alternately back and forth when the warp guides stand in their normal positions, and means for causing the shuttle to travel alternately back and forth along the shuttle guide when the sword arms stand in their normal positions.

5. In a machine of the class described, the combination of upper and lower companion sets of relatively movable reed dents, a suitable oscillatable frame wherein said reed dents are mounted, upper and lower sets of relatively vertically movable warp guides, upper and lower sets of relatively fixed warp guides, a traveler, means for causing said traveler to travel between said sets of warp guides when the relatively movable warp guides stand in their normal positions, a shuttle guide carried by the aforesaid frame, a shuttle traveling in said guide, means for moving the reed dents into operative engagement with respect to each other, means for moving said frame forward and back for the purpose of packing a weft, means for relatively moving the upper and lower sets of movable warp guides to thereby cause said guides to reverse their positions, means for causing the traveler to advance alternately back and forth when the warp guides stand in their normal positions, and means for causing the shuttle to travel alternately back and forth along the shuttle guide when said frame stands in its normal position.

6. In a machine of the class described, the combination of an oscillatable reed having companion sets of relatively movable reed dents, upper and lower sets of relatively vertically movable warp guides, upper and lower sets of relatively fixed warp guides, a traveler, means for causing said traveler to travel between said sets of warp guides when the relatively movable warp guides stand in their normal positions, a shuttle guide mounted on the reed, a shuttle traveling in said guide, means for moving the companion reed dents into operative engagement with respect to each other, means for moving the reed forward and back for the purpose of packing a weft, means for relatively moving the upper and lower sets of movable

warp guides to thereby cause said guides to reverse their positions, means for causing the traveler to advance alternately back and forth when the warp guides stand in their 5 normal positions, and means for causing the shuttle to travel alternately back and forth along the shuttle guide when the reed stands in its normal position.

7. In a machine of the class described, the 10 combination of a movable reed having companion sets of relatively movable reed dents, upper and lower sets of relatively vertically movable warp guides, upper and lower sets of relatively fixed warp guides, a traveler, 15 means for causing said traveler to travel between said sets of warp guides when the relatively movable warp guides stand in their normal positions, means for moving the reed dents into operative engagement with respect to each other, means for moving the 20 reed forward and back for the purpose of packing a weft, means for relatively moving the upper and lower sets of movable warp guides to thereby cause said guides to reverse 25 their positions, and means for causing the traveler to advance alternately back and forth when the warp guides stand in their normal positions.

8. In a machine of the class described, the 30 combination of upper and lower sets of relatively movable warp guides, upper and lower sets of relatively stationary warp guides, a traveler working between said sets of warp guides when the relatively movable warp 35 guides stand in their normal positions, means for causing the traveler to advance alternately back and forth when the warp guides stand in their normal positions, a shuttle, means for causing said shuttle to travel alternately back and forth when the movable 40 warp guides stand in reversed positions, and means for packing a weft.

9. In a machine of the class described, the 45 combination of upper and lower sets of relatively vertically movable warp guides, upper and lower sets of relatively fixed warp guides, a traveler adapted to work between the relatively movable warp guides when the

same stand in their normal positions, means for moving said traveler alternately back 50 and forth when the relatively movable warp guides stand in their normal positions, means for reversing the positions of the relatively movable warp guides, means for packing up a weft, and means for introducing a weft 55 between the warps when the relatively movable warp guides stand in reversed positions.

10. In a machine of the class described, the combination of upper and lower sets of relatively vertically movable warp guides, 60 upper and lower sets of relatively fixed warp guides, a weft-carrying device adapted to work between the relatively movable warp guides when the same stand in their normal positions, means for moving said 65 weft carrier alternately back and forth when the relatively movable warp guides stand in their normal positions, means for reversing the positions of the relatively movable warp guides, means for packing up a weft, and 70 means adjacent to said packing means for introducing a weft between the warps when the relatively movable warp guides stand in reversed positions.

11. In a machine of the class described, 75 the combination of upper and lower sets of relatively vertically movable warp guides, upper and lower sets of relatively fixed warp guides, a traveler adapted to work between the relatively movable warp guides when the 80 same stand in their normal positions, means for moving said traveler alternately back and forth when the relatively movable warp guides stand in their normal positions, means for reversing the positions of the relatively 85 movable warp guides, said traveler remaining idle while the movable warp guides stand in reversed positions, means for packing up a weft, and means for introducing a weft between the warps when the relatively 90 movable warp guides stand in reversed positions.

JOHN C. BROOKS.
